SIGNALING APPARATUS

Johannes Gndl, Chicago, Ill.

Application September 2, 1938, Serial No. 228,175

13 Claims. (Cl. 177—337)

The present invention relates to improvements in signaling apparatus, and more in particular to improvements in traffic signaling apparatus such as is used to control vehicular traffic at street intersections. The object of the invention is to provide more efficient and satisfactory signaling apparatus of this character than has been available heretofore.

A special object of the invention is to provide, in addition to the usual stop and go signals, a progressively movable signal which will at all times indicate to traffic the instant condition of the stop or go signals, as the case may be, as regards the time such signals have been on and the time remaining before a change will occur.

A further object of the invention is the provision of arrangements for a signaling apparatus of this general character whereby the duration of the stop and go periods can be regulated or controlled at will from a remote point, preferably a central control station for controlling a plurality of such signals.

A further object of the invention is the provision of simple and efficient supervisory circuits whereby the dispatcher at the control station can readily supervise the operation of the signaling apparatus at a remote street intersection.

Other objects and features will be explained more in detail hereinafter in the course of a description of the invention with reference to the accompanying drawings, in which—

Fig. 1 is a general view of the complete traffic signal as seen from the street;

Fig. 2 is a section on the line 2—2, Fig. 1, showing among other details part of the mechanism for driving the progressively movable signals;

Fig. 3 is another view of the drive mechanism, with the casing and other parts removed;

Fig. 4 is a rear view of a colored glass disc or panel which is associated with one of the progressively movable signals; and

Fig. 5 is a diagrammatic circuit drawing showing a complete signaling apparatus with the means for controlling and supervising it from a remote control station.

Referring to Fig. 1, the reference character 2 indicates a base, which supports the casing 4 on a column or post 3. The base 2 may be located at the center of a street intersection and is preferably of concrete or other substantial construction. It has a space inside beneath the post 3 and functions also as a housing for certain parts of the apparatus. This space may be accessible through a door 5 at one side of the base, as indicated in the drawings. The post 3 and the

casing 4 may be of any suitable construction, as shown, although the former may conveniently be made of a section of steel pipe.

To avoid confusion in further explanation it will be assumed that Fig. 1 shows the signaling device as seen from the south. The directions are all indicated in Fig. 2. All four sides of the casing are equipped in the same manner and consequently an explanation of the south side which appears in the drawings will suffice.

The reference characters 6 and 7 indicate windows of green and red glass, respectively, behind which are positioned the lamps 9 and 11, shown in dotted lines. These are the usual red and green stop and go lights, and may be provided with the hoods 12 and 13.

Between the stop and go lights there is located a composite glass panel or window indicated generally by the reference character 8. This panel is shown in detail in Fig. 4, which is a view from the inside of the casing. As shown, the panel comprises a disc of uncolored glass 14 on the back of which is secured, by means of transparent cement, a smaller opaque disc 22, two segments 16 and 17 of yellow glass, and two segments 15 and 18 of green and red glass, respectively. The complete panel is held in position by members 19 and 20 at the sides and by a member 21 at the bottom. Behind the composite panel 8 there is a lamp 10, which is rotated in a clockwise direction by mechanism which will shortly be described.

As mentioned hereinbefore, the signaling device presents the same appearance from the north, west, and east as from the south; that is, all four sides are equipped with stop and go lights and with a rotating lamp behind a composite panel. These rotating lamps function as warning signals to indicate an impending change from stop to go, and vice versa, and also function to give the yellow neutral signal.

Referring now to Figs. 2 and 3, the mechanism for rotating the lamps such as 10 will be explained. The source of power is a variable speed motor 59, which may be a series wound direct current motor. This motor drives a shaft 55 by means of the worm 59 and gear 57. Mounted on the shaft 55 is a single toothed pinion 56 which rotates the gear 54, one tooth for each complete rotation of the shaft 55. These parts are conventionally shown and are located in the base 2. It will be understood that suitable accessories such as bearings for the shafts are provided.

The gear 54 is mounted at the lower end of the

main drive shaft 30, which extends vertically upward through the pipe 3 into the casing 4. The pipe 3 also extends within the casing for a short distance and at the top is provided with a cap member 53 which provides a bearing for shaft 30 and also supports the ring 50 by means of two brackets 51 and 52. The ring 50 affords means for mounting various parts, including the four short horizontal shafts 36, 37, 38, and 39. The shaft 36 has bearings in a U-shaped bracket 40 which is seen clearly in Figs. 2 and 3 and which is attached securely to the ring 50. Shafts 37, 38, and 39 are similarly supported in bearings in brackets 41, 42, and 43. The gear 31 is supported on the upper end of shaft 30 and drives the shafts 36, 37, 38, and 39 through the medium of gears 32, 33, 34, and 35, respectively. The gear ratio is 2 to 1.

At the outer end of shaft 36 there is secured an arm 44 on which is mounted a guard or holder 26 for the lamp 23. The holder is open only in front or toward the composite panel illuminated by lamp 23 and confines the illumination thereof to a section the width of the yellow section 16 or 17. The holder also serves as a reflector. The arrangements for lamps 24, 25, and 10 are the same as that described in the case of lamp 23. That is, these lamps are provided with holders 27, 28, and 29, which are supported on arms 45, 46, and 47, attached to shafts 37, 38, and 39, respectively.

The electrical connections for lamp 23 include a brush holder 64 mounted on the ring 50 and having a brush which presses against the slip ring 60 on shaft 36. The shaft 36 is preferably hollow. The slip ring 60 may have a conductor attached to it which passes through a small hole into the hollow shaft 36 and thence through the shaft to one terminal of the socket in which lamp 23 is mounted. The other terminal of the socket 40 may be grounded. Lamps 24, 25, and 10 are similarly connected through slip rings 61, 62, and 63, and brush holders 65, 66, and 67.

For the purpose of controlling certain circuits, the shaft 38 is provided with a cam 68 and the shaft 39 is provided with two cams 69 and 70. Each cam operates a set of contact springs which is suitably supported on the ring 50. The shape of the cams and the arrangement of the different sets of contact springs controlled thereby can be best understood from Fig. 5, in connection with which these parts will be more fully explained shortly.

The direction of rotation of shaft 30 is clockwise, as seen from the top, as in Fig. 2, which means that each of the lamps such as 10 rotates in a clockwise direction, as seen from in front. Being driven from the same shaft 30, through the medium of bevel gear 31 and identical gears 32-35, these lamps always rotate in synchronism and at all times occupy corresponding positions in rear of their associated panel, with the exception that the west and east lamps 25 and 23 are displaced 180° from the north and south lamps 24 and 10. The lamps do not rotate continuously, but advance step by step or intermittently, due to the arrangement including the gear 54 and the single toothed pinion 56. The number of teeth on the gear 54 bears a special relation to the subdivisions of the panel such as 8. Referring to Fig. 4, each yellow segment subtends an arc of 20°, and the green and red segments subtend arcs of 160° each. The gear 54 has 36 teeth. It will be understood now that at each rotation of shaft 55, gear 54 will be ro-

75 tated the distance of one tooth, or 10°, and that since the gear ratio between gear 31 and gears such as 32 is 2 to 1, the shafts such as 36 will be rotated 20°. This distance corresponds to the width of the yellow segments 16 and 17, and is one-eighth the width of the green and red segments. The lamps such as 10, therefore, have eighteen different positions, as indicated in Fig. 1, which shows the lamp 10 and indicates its positions in radial dotted lines. In two of these positions the lamp 10 is in the rear of one or the other of the yellow segments; in eight positions it is in rear of the green segment; and in the eight remaining positions it is in rear of the red segment.

Referring now to Fig. 5, the lamps 23, 24, 25, and 10 are indicated diagrammatically at the left, with their associated slip rings and brushes. These parts bear the same reference numerals as in Fig. 2. The cam 68 on shaft 38 is shown also, together with the contact sets controlled thereby. There are two of these contact sets, one comprising the movable or working contact springs 109 and 101, and the other comprising similar contact springs 102 and 103. The cams 69 and 70 on shaft 39 are also shown. The former controls a contact set comprising working contact springs 104 and 105, and the latter controls the working contact spring 106. It will be understood that in each case the working contact springs are tensioned against their associated cams.

The drawing also shows the green go lamp 9, located on the south side of the signaling device, together with the remaining green lamps 110, 111, and 112, which are located on the north, west, and east sides, respectively, as indicated. The four red lamps for the stop signals are in a group below and are indicated by the reference numerals 11, 113, 114, and 115.

The reference character S1 indicates a step-by-step switch comprising the stepping magnet 123, the wiper 120, and a bank of five contacts, as indicated. This switch may be of the well known type in common use in automatic telephone systems, and for other purposes, and is more fully disclosed in U. S. patent to Erickson, No. 1,794,888, granted March 3, 1931. The operation of a switch of this type is well understood, but it may be stated that the wiper is advanced on the deenergization of the associated stepping magnet rather than upon the energization thereof, and that the wiper has a forward movement only. In the case of switch S1, for instance, the wiper 120 is shown in engagement with the fourth contact in its bank. On energization and deenergization of the magnet 123, the wiper will be advanced one step into engagement with the fifth contact, and one additional step will bring the other end of the wiper into engagement with the first contact.

Switches S2, S3, and S4 are similar to switch S1. The two former are exactly the same as switch S1, and switch S4 is of similar construction, but has two wipers 140 and 141, and each wiper has six contacts in its bank.

The reference character B indicates a battery for supplying operating current. Suitable automatic charging equipment may be provided to keep the battery charged, but as this is of well known construction and has nothing to do with the invention, it is now shown herein. The relays 128 and 127 are provided for starting and stopping the operation of the signaling device

by connecting and disconnecting the battery B, as will be explained shortly.

Relays 142, 143, and 144 are control relays which are associated with the line comprising conductors 150 and 151 extending to the control station. Conductor 150 is used for operating the switches S4, S1, S2, and S3, while conductor 151 is used for supervision.

The parts just described, including the switches, relays, and the battery B, may be located in the base, suitable mounting provisions of known character being provided. The wiring may also be of any approved character, and will necessarily include a cable extending through the post 3 to connect the parts in the base with those in the casing 4.

The equipment at the control station comprises the switching key K1, the voltage control key K2, the battery B2, the key or push button P, the supervisory lamp L, and the milliammeter M. The latter has associated with it a variable resistance for adjustment purposes. All of this equipment except the key K1 and lamp L may be common to other control lines such as the line comprising conductors 150 and 151.

The operation of the complete signaling device and the controlling equipment will now be explained, reference being had especially to Fig. 5. It will be assumed that all the parts are in the position in which they are shown. It will be understood, therefore, that the signaling device is not operating, as relay 128 is deenergized and the battery B is disconnected from conductor 160, over which current is supplied to the motor 59 and to the various lamps of the signaling device.

In order to place the signaling device in operation, the dispatcher will first actuate the key K1 to associate the common equipment at the control station with the control line 150-151. Upon the actuation of the key, a circuit is completed from battery B by way of the resistance 136, wiper 141 of switch S4, contact 147 of relay 144, line conductor 151, key K1, the milliammeter M, and the variable resistance 148 to ground. The value of the resistance 136 may be such that with the battery B in its average state of charge a current of 40 milliamperes will flow over the above circuit. The milliammeter may have a range of 0 to 100 milliamperes. These values are, of course, given merely by way of example. Noting the reading of the milliammeter M, the dispatcher is informed thereby that switch S4 is in position 1, as only in this position are the circuit conditions such that a reading in the vicinity of 40 can be obtained. If the reading is not exactly 40, the dispatcher may make the necessary adjustment of the variable resistance 148, so that subsequent readings will be exactly in accordance with the values selected to convey the different items of information which the dispatcher obtains over the supervisory circuit.

The dispatcher now operates the push button P five times in order to advance the switch S4 five steps into position 6, which is the starting position. Each time the push button is actuated a circuit is completed by way of a section of battery B2, key K2, push button P, key K1, line conductor 150, and relays 142 and 143 to ground. Relay 142 is marginally adjusted and does not operate over the above circuit. Relay 143 operates each time the circuit is closed, and accordingly transmits five impulses to the stepping magnet 126 of switch S4. On each impulse the magnet energizes and deenergizes, which ad-

vances the wipers 140 and 141 one step, with the result that after five impulses have been transmitted the wipers will have been advanced to position 6. While transmitting impulses to magnet 126, the relay 143 also transmits impulses to the slow-releasing relay 144, which energizes and due to its slow-releasing characteristic stays in operated position throughout the series of impulses, holding open the supervisory circuit at contact 141. At the end of the series of impulses relay 144 deenergizes and closes the supervisory circuit.

In position 6 of switch S4 the supervisory circuit includes the resistance 132, the value of which may be such that the milliammeter M will show a reading of 10. Being thus advised that the switch is in the desired position, the dispatcher will actuate the key K2 and will then operate the push button P again to send another impulse over line conductor 150. With key K2 actuated, the circuit includes the entire battery B2 and both relays 142 and 143 are energized, with the result that a circuit is closed in an obvious manner through contacts 146 and 145 and wiper 140 in position 6 to the relay 128. On reenergizing, relay 128 locks itself at contact 130 and connects the battery B to conductor 160 at contact 129.

The supervisory circuit is momentarily opened by relay 144 during the foregoing operation, of course, but is again closed after relay 128 has energized. It should be noted at this point that the dispatcher is advised of the proper energization of relay 128 by the slight decrease in the reading of the milliammeter, due to the slight fall in potential at battery B when current consumption, due to operation of the signaling device, begins. The change in the reading will be very small, but is sufficient to be detected. If desired, a very low resistance 134 may be inserted in series with the battery, but ordinarily will not be required. Contacts on relay 128 could be employed to vary the value of resistance 132, but such arrangement would merely indicate the energization of relay 128, and the arrangement shown is therefore to be preferred as it depends on actual current drain from battery B, which can only take place by the operation of the signaling device.

When the battery B is connected to conductor 160 as previously described, circuits are completed for lighting the lamps 23, 24, 25, and 10, and also a circuit is completed for the motor 59, the latter circuit extending through the motor and by way of resistance 157, wiper 122 of switch S3, conductor 165, and contact spring 105 to ground. The lamps mentioned light up, and the motor 59 starts. As will be noted, this cycle of the operation requires that contact 105 is closed as shown in the drawings, connecting ground to conductor 165 and wiper 122 of switch S3. In other words, the cam 69 must have come to rest at the end of a previous operation, when the system was switched off, in the position in which it is shown. It may happen, however, that the system is switched off when this cam is in an off-position, keeping the contact 105 open. In this case, cam 68 would also be at a corresponding angular off-position and would keep closed either the contacts 100 or 102. In the first case, ground would be supplied for the operation of the motor 59 over wiper 120 of switch S1, or, in the second case, over conductor 163 and wiper 121 of switch S2. Motor 59 therefore starts operating in any case. The speed of the motor is determined by the value of the resistance over

which its starting circuit is closed, in the first assumed case by the value of resistance 157. All four of the lamps 23, 24, 25, and 19 are in horizontal positions in rear of yellow segments in their associated panels, and consequently the signalling device displays a yellow or caution signal in all directions.

As the motor continues to drive shaft 55, the single tooth on pinion 56 will eventually engage gear 54 and will rotate said gear the distance of one tooth, or 10°, as previously explained. The four shafts 36-39 are accordingly rotated 20°, and the four lamps 23, 24, 25, and 10 are advanced the same distance to their next positions. In the case of lamp 10, the next position is in rear of the green segment and the same is true of lamp 24 on the north side of the signalling device. Lamps 25 and 23 on the west and east sides, respectively, are displaced 180° from lamps 24 and 10, and accordingly move to positions in rear of the corresponding red segments.

When the shafts 38 and 39 are rotated as described, the cams 68, 69, and 70 are also rotated, with the result that conductors 161 and 162 are grounded by springs 100 and 101 associated with cam 69, while ground is removed from conductor 165 at contact spring 165 associated with cam 69. The grounding of conductor 162 establishes a new circuit for motor 59, said circuit including the wiper 120 of switch S1 and resistance 155. The grounding of conductor 161 completes circuits in an obvious manner for the green lamps 110 and 9 on the north and south sides of the signalling device. The lamps accordingly display a go signal for north and south traffic. The grounding of conductor 161 also completes circuits for the red lamps 114 and 115 on the west and east sides of the signalling device, and these lamps accordingly display stop signals.

As the motor 59 continues to run, at a speed determined by the value of resistance 155, the lamps 24 and 19 are intermittently advanced to successive positions behind the green segments in their associated panels, and lamps 25 and 23 are similarly advanced to successive positions behind the red segments in their associated panels. These lamps accordingly show by their positions the approximate length of time that the go and stop signals have been on, and as they reach their last positions next to the yellow segments they give warning of the impending change.

When the shafts 38 and 39 have rotated 180° from the position shown in the drawings, conductor 165 will again be grounded by cam 69, and ground will be removed from conductors 161 and 162 by cam 68. The motor 59 now runs for an interval at a speed determined by resistance 157, and the lamps 110, 9, 114, and 115 are extinguished. Lamps 23, 24, 25, and 10 display caution signals.

On the next rotation of shafts 38 and 39, cam 68 operates springs 102 and 103 to ground conductors 163 and 164, and cam 69 removes ground from conductor 165. By the grounding of conductor 163 a new circuit is completed for motor 59, the circuit including the wiper 121 of switch S2 and resistance 156. By the grounding of conductor 164, circuits are completed for red lamps 113 and 11 and for green lamps 111 and 112. Stop signals are thus displayed to north and south traffic and go signals to west and east traffic. The rotation of shafts 36-39 has also advanced the lamps 24 and 10 into their first positions in rear of the red segments of their

associated panels, while lamps 25 and 23 have been advanced to their first positions in rear of the green segments of their associated panels.

The apparatus continues to operate in the manner described, alternating the north and south traffic with the west and east traffic in a manner which will be clearly understood. Three different circuits are employed for the motor 59, as explained, whereby the duration of the signals north and south and east and west can be adjusted in accordance with traffic requirements.

The manner in which this is done will presently be explained, after first considering the supervisory circuits over which the dispatcher is advised as to the rate at which the signals are changing at any given time and the relative duration of the stop and go periods in any given direction.

Having started the apparatus in operation as described, if the dispatcher desires to check up on the signal changes, he will restore key K2 and transmit two impulses over the line by means of the push button P. In response to these impulses relay 143 energizes twice and transmits two impulses to magnet 126, stepping the switch S4 from position 6 to position 2. In this position of the switch the supervisory circuit extends from battery B by way of conductor 160, conductor 167, resistance 118 (either alone or in parallel with resistance 116 or resistance 117), wiper 141 in position 2, contact 147, conductor 151, switch K1, milliammeter M, and resistance 148 to ground. The resistances 116, 117, and 118 may have such values that with resistance 118 alone in the circuit a reading of 65 will be obtained, resistances 118 and 116 in parallel will give a reading of 80, while resistances 118 and 117 in parallel will give a reading of 95.

To explain how these readings are correlated with the operation of the signalling device, it will be assumed that when the supervisory circuit is closed, the apparatus is in the position in which it is shown in the drawing, with the yellow signals displayed. In this position, and also in a position 180° farther on, cam 69 connects resistance 116 in parallel with resistance 118 at contact 104, giving a reading of 80 on the milliammeter M. This reading, therefore, indicates to the dispatcher that the yellow signals are being displayed.

As the apparatus continues to operate, cam 69 will disconnect resistance 116 and cam 70 will connect up resistance 117. The latter resistance in parallel with resistance 118 gives a reading of 95, which is obtained during the go period for north and south traffic, which corresponds to the stop period for west and east traffic. When the cams have rotated to a position 180° from the position in which they are shown, resistance 116 will again be connected and resistance 117 will be disconnected. The milliammeter will therefore again read 80, indicating the next caution period. As the cams advance again, resistance 116 is disconnected, and as resistance 117 is not connected by cam 70, resistance 118 alone is included in the supervisory circuit, giving a reading of 65. This reading indicates to the dispatcher that the stop signals are being displayed for north and south traffic and the go signals are being displayed for west and east traffic.

Thus the dispatcher, by observing the milliammeter, is able to tell at all times what conditions exist at the signalling device and can time the duration of any particular signal at will.

As the apparatus is shown in the drawings, the north and south go signals will be lighted for much longer periods than the corresponding stop signals; that is, the apparatus is set to handle a much greater volume of traffic north and south than east and west. If traffic conditions should change at a particular time of the day, the dispatcher can alter the stop and go periods accordingly by resetting switches S1 and S2. The manner in which this is done will now be explained.

With key K2 in normal position, the dispatcher first transmits sufficient impulses by means of push button P to restore switch S4 to position 1. These impulses may be spaced sufficiently to allow relay 144 to deenergize after each impulse, and the dispatcher will accordingly be advised of the arrival of switch S4 in position 1 by the milliammeter showing a reading of 40, as previously mentioned. Two more impulses are now transmitted, advancing switch S4 to position 3, in which wiper 140 is associated with the stepping magnet 124 of switch S2. Key K2 is now operated, and the push button P is again operated one or more times, depending on the amount of change that is to be effected. If the relative duration of the stop and go periods is to be exactly reversed, the push button will be operated three times, to transmit three impulses over the line. Relays 142 and 143 respond to these impulses and transmit three impulses to stepping magnet 124 of switch S2, which is accordingly advanced to position 4.

The dispatcher now restores key K2 and operates the push button P to transmit a single impulse over the line, which energizes relay 143 to transmit an impulse to stepping magnet 126 of switch S4. This switch is therefore advanced to position 4, in which wiper 140 is associated with the stepping magnet 123 of switch S1. The key K2 is now again operated, followed by the operation of the push button P a sufficient number of times to advance switch S1 from position 4 to position 1, or two impulses. The dispatcher knows how many impulses to transmit to properly reset switches S2 and S1, either by maintaining a record of the position of the switches, or by timing the stop and go periods prior to the resetting operation to ascertain the instant setting.

The effect of the changed setting of switches S1 and S2 may now be explained briefly. During the period in which the green lamps north and south are lighted to display go signals in these directions, the conductor 162 is grounded and the speed of the motor is governed by the resistance with which wiper 120 of switch S1 is associated. This wiper is now in position 1 instead of position 4 as formerly, and the resistance 170 is in circuit instead of resistance 155. As resistance 170 is of lower value than resistance 155, the motor 59 will now run faster than before, and the go periods for north and south traffic will be correspondingly shortened. The stop periods for west and east traffic, which coincides with the go periods for north and south traffic, will be shortened at the same time. When the stop signals north and south are displayed, the conductor 163 is grounded and the speed of the motor 59 is determined by the value of the resistance with which wiper 121 of switch S2 is associated. This switch has been advanced to position 4, connecting resistance 171 in circuit in place of resistance 156. As the former resistance is greater than the latter, the motor 59 runs slower and the duration of the stop periods

for north and south traffic is increased. At the same time the go periods for west and east traffic are also increased.

It will be apparent that the dispatcher can also regulate the duration of the yellow caution signals by changing the setting of switch S3. This is accomplished by first setting switch S4 in position 2, and by then transmitting the proper number of impulses to reset switch S3 to the desired position, as will be readily understood.

In any position of switch S4 in which it is associated with one of the switches S1, S2, or S3, the supervisory circuit including wiper 141 will be closed so that immediately after any resetting operation has been completed, the dispatcher can check the result by observation of the milliammeter.

During the early morning hours, say from 1:00 a. m. to 5:00 a. m., it may be desirable to stop the operation of the traffic signaling device to avoid delay to the occasional vehicles which may pass during this period. In order to shut down the signaling device, the dispatcher on duty will step switch S4 to position 5 in the manner previously explained and will then, after first actuating key K2, depress the push button P to close a circuit for relay 127. Relays 142 and 143 respond to the actuation of the push button and the circuit for relay 127 is closed over contacts 146 and 145 of these relays and wiper 140 in position 5. On energizing, relay 127 breaks the locking circuit of relay 128, which deenergizes and disconnects the battery B from conductor 169 over which current is supplied to the motor 59, and the various lamps of the signaling device. At the time of shutting down the system, the switches S1, S2, S3 may be in any assumed position, and the control cams 68, 69, 70 may likewise stop either in the positions in which they are shown or in any other position. As previously explained, the system is ready for reoperation regardless of the position of the switches or cams, because ground will be supplied to the motor 59 over one of the conductors 162, 163 or 165, and will complete the motor circuit as soon as battery is again connected to the conductor 160.

The supervisory circuit enables the dispatcher to check the position of switch S4 after it has been set to position 5 (presumably), as in position 5 the resistance 133 is included in the circuit. This resistance has the proper value to give a reading of 20 on the milliammeter M, and if such reading is observed it indicates that switch S4 is in the desired position. By checking the position of the switch in this manner before actuating the push button P, the dispatcher is able to avoid any chance of disturbing switches S1, S2, or S3, due to accidental positioning of switch S4 in position 2, 3, or 4 instead of in position 5. The supervisory circuit also serves to notify the dispatcher that the battery B has actually been disconnected after the shutdown procedure is completed. When the relay deenergizes and opens contact 129 to disconnect the battery B, it breaks the supervisory circuit at this point and the milliammeter reading will drop to zero.

It has been mentioned already that the control equipment shown is common to the line 150—151 and other similar lines. When the control equipment is not in use on line 150—151, it is disconnected therefrom by restoration of key K1. With the key in normal position, conductor 151 is connected to the supervisory lamp L,

which will light up fully only when the supervisory circuit includes resistances 113 and 117 in parallel, which is the condition in which the supervisory circuit has the least resistance. With resistance 113 in the circuit alone, or with resistance 116 in parallel with resistance 113, the lamp L will be correspondingly dimmed. It will be clear therefore that if the dispatcher leaves the switch S4 in position 2, 3, or 4 at the time the key K1 is restored the lamp L will give a continuous supervision of the operation of the signaling device shown. Other signaling devices are of course similarly provided with lamps such as L, so that the dispatcher can watch the operation of the whole system, using the common equipment only when it is necessary to start or stop some signaling device, or reset one or more of the switches.

The invention having been described, what is considered to be new and for which the protection of Letters Patent is desired, will be pointed out in the appended claims.

I claim:

1. In a traffic signaling device, a round transparent panel having red and green sections separated by yellow sections, the yellow sections being equal and disposed 180° apart, the red and green sections also being equal and having an angular width which is an exact multiple of the yellow sections, a light behind said panel, a shaft for rotating said light, and means for intermittently rotating said shaft in steps, the angular distance moved in each step being exactly equal to the angular width of said yellow sections.

2. In a traffic signaling device, red and green lights indicating stop and go, respectively, a third light, means for alternately illuminating said red and green lights, means operating in timed relation with the alternate illumination of said red and green lights for rotating said third light step-by-step through a plurality of fixed positions, and filtering means effective in each said position for causing said third light to give a red or green signal according to whether the said red or green light is illuminated at the time.

3. In a traffic signaling device, red and green lights indicating stop and go, respectively, a third light, a rotatable shaft on which said third light is mounted, means for intermittently rotating said shaft to cause said third light to assume successive stationary positions in a circular path, switching means, cam means on said shaft for operating said switching means during non-successive movements of the shaft, and circuits controlled by said switching means for alternately illuminating said red and green lights.

4. In a traffic signaling device, red and green lights indicating stop and go, respectively, a third light, means for alternately illuminating the said red and green lights, means for intermittently rotating said third light in timed relation therewith, means including a red and green filter panel in front of said third light to associate the same with either the stop light or the go light, depending on which one is illuminated, and shielding means associated with said third light for confining the illumination of said panel to an area which is equal to the total area of the panel divided by the number of movements of said third light required for a complete rotation thereof.

5. In a traffic signal, a source of light, means for rotating said light in a series of steps, in-

cluding means for holding said source stationary between successive steps, means for causing said source to display a particular traffic control signal in one of its stationary positions, and means for causing said source to display a different traffic control signal in another stationary position.

6. In a traffic signal, a source of light, means for rotating said light in a series of steps, in-
10 cluding means for holding said source stationary between successive steps, means for causing said source to display a particular traffic control signal in one of its stationary positions, and means for causing said source to display two additional traffic control signals in two other stationary positions, respectively.

7. In a traffic signal, a source of light, means for supporting said source in a plurality of different stationary positions, intermittently operated means for moving said source to its different positions successively, means for causing said source to display a caution signal while remaining stationary in one position, and means for causing said source to display a traffic control signal in each of a plurality of its other positions.

8. In a traffic signal, a source of light, means for rotating said source in a series of steps, in-
30 cluding means for holding said source stationary between successive steps, means for causing said source to display a caution signal in one of its stationary positions, means for causing said source to display a stop signal in another of its stationary positions, and means for causing said source to display a go signal in another of its stationary positions.

9. In a traffic signal, a source of light, means for rotating said source in a series of steps, in-
40 cluding means for holding said source stationary between successive steps, two filtering mediums located in front of said source when the same is in two adjacent stationary positions, respectively, each said medium being adapted to transmit a different color of light, and means effective when the said source is in either of said positions for preventing said source from transmitting light to the filter medium in the other position.

10. In a traffic signal, a source of light, means for rotating said source in a series of steps, in-
50 cluding means for holding said source stationary between successive steps, means for confining the light transmitted from said source to a beam of limited cross-sectional area, and a plurality of light filtering mediums on which said beam impinges, the area of each said medium being equal to or an exact multiple of the cross-sectional area of said beam, and the said steps being so adjusted as to length and starting position that in each stationary position of said source the said beam impinges on only one filtering medium.

11. In a traffic signal, a display panel comprising different light filtering mediums each having an area which is an exact multiple of a pre-determined unit area, a light source behind said panel, means for causing said source to illuminate only one said unit area at a time, and means for moving said source at spaced intervals through a predetermined distance equal to the distance between the centers of adjacent unit areas, whereby said unit areas are illuminated successively.

12. In a traffic signal, a display panel comprising two different colored filter sections adapted to signal stop and go, respectively, and an intervening filter section adapted to signal caution, a light source behind said panel, means for re-

stricting the light reaching said panel from said source to an area equal to the area of said caution section, and means for moving said source in steps separated by stationary periods in one of which said source illuminates only the said filter section which signals caution, whereas in the next preceding and following periods the said source illuminates only the stop and go filter sections, respectively.

13. In a traffic signal, a light source, means supporting said source for rotation in a circular path, means for giving said source an intermittent motion along said path, whereby said source

is caused to occupy successive stationary positions, a display panel in front of said source, means for causing said source to illuminate different distinct areas of said panel in the successive positions occupied by said source, respectively, and different colored filter sections composing said panel, each section having an area equal to or an exact multiple of the area illuminated by the said source, the said sections being so arranged relative to the stationary positions of said source that parts of two adjacent sections are not illuminated in any stationary position.

JOHANNES GANDL.
